UNITED STATES PATENT OFFICE.

JAMES CARR TROVILLION, OF TUNNEL HILL, ILLINOIS.

CLAMPING DEVICE FOR WIRES.

SPECIFICATION forming part of Letters Patent No. 373,789, dated November 22, 1887.

Application filed August 18, 1887. Serial No. 247,247. (No model.)

To all whom it may concern:

Be it known that I, JAMES CARR TROVILLION, a citizen of the United States, and a resident of Tunnel Hill, in the county of Johnson 5 and State of Illinois, have invented certain new and useful Improvements in Clamping Devices for Wires; and I do hereby declare that the following is a full, clear, and exact description of the invention, which will enable others 10 skilled in the art to which it appertains to make and use the same, reference being had to the accompanying drawings, which form a part of this specification, and in which—

Figure 1 is a side view of my new and improved clamping-device for wires for use in the construction of wire fences, showing the same in its open position for placing the wire therein. Fig. 2 is a side view showing the device closed or clamped on a wire. Fig. 3 is a 20 view of the recessed circular main block of the clamping device. Fig. 4 is a view of the slotted wedge-shaped block, and Fig. 5 is a longitudinal sectional view of the wedge-shaped block.

25 The same letters of reference indicate corresponding parts in all the figures.

My invention consists in a new and improved clamping device for use in the construction or building of wire fences, and it will be herein- 30 after fully described and claimed.

Referring to the several parts by letter, A indicates the main part of my clamping device or the larger clamping-block thereof, and consists of a block which is here shown as circular in form, but which may of course be square or of any other suitable shape. This main block A is formed in one of its sides with the deep recess or opening B, which is inclined or wedge-shaped, being larger at one end than 35 at the other, and in one of the flat sides of this recess is formed a dovetailed groove or recess, C, into which is slid or forced a steel clamping-plate, D, the outer face of which is formed with the inclined serrations E; and by forming the opening or recess C with the dovetailed ends the steel clamping-plate can be removed to be recut when it becomes worn by use.

On the side of the main block A, to one side of its central deep recess or opening, B, is 45 formed an inwardly-projecting block or lip, F, having the transverse opening G through its inner end, through which passes the remova-

ble screw or bolt H, for the purpose herein-after specified. The main block A with its lip F are cast integral, of malleable iron, preferably.

I indicates the sliding wedge-shaped block of the clamp, which is also formed of malleable iron and of the size shown, being as thick as the depth of the deep recess or opening B, in which it slides, so that its outer face is flush with that outer side of the block A. This block I is wedge-shaped and has formed in one of its edges or sides a dovetailed groove, J, in which fits a steel clamping-plate, K, the outer face of which is formed with the inclined serrations L, this steel clamping-plate being so located in the side of the block I that when the said block is drawn into its operative position its steel serrated clamping-plate will be directly opposite to the steel clamping-plate of the block A. By forming the groove or recess J with the dovetailed ends the steel clamping-plate K can be removed, to be recut when its operative face becomes worn by long use. 75 Near its opposite edge the wedge-shaped block I is formed with the longitudinal slot M; and when this block is placed in position in the deep groove or recess in the main block A it is secured from falling out by the screw or bolt H, which passes through the perforated inner end of the lip F, through the said longitudinal slot M, and has its inner end inserted in the bottom of the recess B, the inner half of the lip F extending with its flat inner 80 side over that half of the wedge-shaped block I over its slotted portion and assisting in holding the said block in place in the recess in which it slides. The shouldered smaller outer end of the wedge-block I is cast with a central pillar, N, having a shouldered threaded outer end, O, and on this pillar is swiveled a block or collar, P, having the ring Q, and held in position on the pillar by a nut, R, as most clearly shown in the sectional view, Fig. 5, of 85 90 95 the drawings.

In operation, in stretching a wire from post to post in the construction of wire fences, the loose or free-end portion of the wire is placed between the recessed sides of the block A and 100 of the wedge-block I, which are provided with the serrated steel clamping-plates, the wedge-block being pushed open, as shown in Fig. 1 of the drawings, when, by drawing on the

smaller ringed end of the wedge-block, the said block is drawn along through the wedge-shaped opening B in the block A until the wire is tightly seized between the said steel 5 clamping-plates on the adjacent sides of the recesses in the block A and of the wedge-shaped block I. The said serrated plates will firmly seize the wire and effectually prevent it from slipping, and it will be readily seen that, owing 10 to the wedge shape of the recess or opening B in the main block A and the wedge shape of the sliding block I, the more force or power that is applied to the outer ringed end of the wedge-block I the tighter will the wire be held 15 in the clamping device.

From the foregoing description, taken in connection with the accompanying drawings, the construction, operation, and advantages of my new and improved clamping device will 20 be readily understood.

It will be seen that my new and improved device is simple and strong in construction and can be manufactured at a small cost, while it is exceedingly effective and satisfactory in 25 its operation. It possesses great durability and is easy in operation, while it is cheap in construction, the swiveled ring adding to the convenience and ease with which it may be employed; and it will be found that the wire 30 will not slip in the clamp while being stretched, and will not be bent, as it is held between the long straight clamping-sides of the blocks in the device.

My new and improved clamping device can be attached to a suitable ratchet-lever, or the 35 farmer can use a plain wooden bar, five feet long and of suitable diameter, in connection with the clamping device, as will be readily understood.

Having thus described my invention, what I 40 claim, and desire to secure by Letters Patent of the United States, is—

The combination of the main block formed with the wedge-shaped opening having the dovetailed recess in one of its sides, and having 45 the integral inwardly-projecting perforated lip and the steel clamping-plate fitting in the said recess and formed with the corrugated outer surface, the screw-bolt, the wedge-shaped block having the longitudinal slot and 50 having the dovetailed recess formed in one of its sides and formed with the pillar on its shouldered smaller end, having the retaining-nut, the steel clamping-plate fitting in the said recess and formed with the corrugated 55 outer surface, and the ring having the collar or sleeve, substantially as and for the purpose set forth.

In testimony that I claim the foregoing as my own I have hereunto affixed my signature 60 in presence of two witnesses.

JAMES CARR TROVILLION.
